(57) **CLAIM**

The ornamental design for the steam generator, as shown and described.

DESCRIPTION

FIG. 1 is a perspective view of the steam generator.

FIG. 2 is a right side view of the steam generator.

FIG. 3 is a left side view of the steam generator.

FIG. 4 is a front view of the steam generator.

FIG. 5 is a back view of the steam generator.

FIG. 6 is a top view of the steam generator; and,

FIG. 7 is a bottom view of the steam generator.

The details shown in broken lines form no part of the claimed design.
